UNITED STATES PATENT OFFICE.

WILBER E. ARNOLD, OF CINCINNATI, OHIO.

SAFE.

1,084,837.

Specification of Letters Patent.

Patented Jan. 20, 1914.

Application filed April 30, 1913. Serial No. 764,540.

To all whom it may concern:

Be it known that I, WILBER E. ARNOLD, a citizen of the United States, residing at Cincinnati, in the county of Hamilton and 5 State of Ohio, have invented certain new and useful Improvements in Safes, of which the following is a specification.

My invention relates to fire-proof safe construction and its object is to reduce the 10 expense of transportation and installation, and at the same time provide a more reliable construction in a fire-proof safe.

My invention consists in the parts and in the details of construction and arrangement 15 of parts hereinafter more fully described and claimed.

In the drawing: Figure 1 is a perspective view of a safe embodying my invention, the outer door being represented as open and 20 the interior details being illustrated by dotted lines. Fig. 2 is a vertical section on the line $x-x$ of Fig. 1. Fig. 3 is a vertical section on the line $y-y$ of Fig. 1. Fig. 4 is a detail perspective view of the main shell 25 ready to receive the front and rear plates. Fig. 5 is a vertical cross-section, corresponding to the one of Fig. 2, but showing the parts in position in a mold and the cement being poured into the mold. Fig. 6 is an enlarged detail of one of the rear corners, on the line $z-z$ of Fig. 1, showing the rear 30 plate attached to the flange of the main shell and showing how the binders are secured around the inner casing thus made up of the 35 plates.

The main shell plate 1 is bent to form the main shell, being originally an elongated rectangular plate, and having slits 2 at the intervals where the corners of the main shell 40 are to be, so that when the plate is bent up, portions of the plate along the edges between the slits may be bent at right angles to the main plate, thus forming the rear flanges 3 and the forward flanges 4. These 45 flanges have holes receiving rivets 5. The ends of the rectangular plate have portions 6 and 7, overlapping near one corner, and these portions are riveted together. This much of the construction is clearly seen in 50 Fig. 4. The rear plate 8 is riveted to the rear flanges 3 and the striking plate 9 is riveted to the forward flanges 4, with edges being approximately flush with the inner sides of the main shell, and it is against this

striking plate that the outer door 10 abuts 55 when closed. A front plate 11 is riveted to the shell along with the striking-plate 9, this front plate 11 having an opening into which the door 10 fits. This outer door 10 may be of any approved construction, such 60 as with the bolt frame 12 on its inside, fitting closely within the opening of the striking-plate 9 and the inner sides of the main shell. Bolts 13 may be provided, and any approved locking device, such as the handle 65 14 and the knob 15 represent, may be provided for the outer door. The outer door hinges 16 are riveted to the front plate 11. The inner door 17 has its hinges 17^a secured 70 to the inner side of the main plate and 70 abuts against the stop 18 riveted around the inner sides of the main shell. This door is provided with a suitable lock 19.

From the above it will be seen that a complete closure is made, corresponding to the 75 inner structures of safes as they have been constructed, but widely different from the former structures in the details thereof. This inner structure is made complete and self-contained, whereas the inner parts of 80 safes which have outer plates and angles outside the fire-proof material are of construction dependent upon the outer structure. I prefer the use of the two doors with the air space between them for the front of 85 the safe. It will be understood that these doors, the outer door especially, may be constructed in any approved manner to diminish air currents into the safe, as well as to be secured against most attempts at 90 burglary. This entire inner structure is made with a view to receive the cement or other fire-proof material around the four sides and the back to afford the proper insulating and heat-resisting wall in each of these regions, 95 while relying upon the air space between the two doors to serve these purposes in front. It will of course be understood that a door provided with such insulating and heat-resisting material might be substituted 100 in the front of the safe as well. However, I find that the air space for the front is as effective as the fire-proof doors usually provided on safes or vaults.

As a binder for the fire-proof material a 105 series of strands of metal is provided throughout the sides and back and spaced away from the plates thereof, so as to lo-

cate the binding structure about midway of the depth of the material as it is provided over the surfaces of the plates.

For the binder, a woven wire screen or cloth of coarse mesh and moderately heavy wire may be used with advantage, as I have illustrated herein. Such woven wire structure may be obtained of a width to fit between the rear and front flanges 3 and 4, 6 around the sides of the main shell. It is preferably provided in two layers 20 and 21, the first separated from the adjacent main shell plate by spacing pieces 22 lying against the outer sides of the shell plates near 10 the corners of the shell, as best seen in Fig. 3. The second layer 21 passes around, being spaced away from the first layer 20 by other spacing pieces 23 resting on the first or inner layer 20. The ends of these webs or layers 15 20 and 21 are tightly clenched where they come together so that they bind tightly around the sides of the shell and hold the spacing pieces 22 and 23 in position while these webs are held apart in all regions due 20 to the tension on them as stretched over said spacing pieces. Similarly, the rear plate 8 has two layers or webs 24 and 25 stretched across it, these webs passing over spacing pieces 26 and 27, respectively, near the opposite edges of the rear plate 8 and passing 25 over the edges of the rear plate and the flanges 3 to which it is riveted, and being clenched to the adjacent regions of the webs 20 and 21 stretched around the main shell. 30 It will be understood that these rear webs 24 and 25 may stretch in either or both directions across the rear, and may be drawn tight so that they remain separate from each other and from the rear plate, due to 35 their tension while at the same time holding the spacing pieces 26 and 27. For attaching these webs to the other webs 20 and 21 around the edges of the rear plate 8 and the flanges 3, strong clips 28 may be used, 40 as is best seen in Fig. 6.

The structure thus far described, thus made up with all parts held securely in position, is ready upon arrival at the point of use for the completion of the safe without necessity of any further skilled labor 45 of the safe worker thereon. For this, I prefer to provide a suitable mold 29, such as the strong wooden box illustrated in Fig. 5, which is preferably shipped from the factory with the inner structure, constituting the packing and shipping case therefor. The inner walls of this box or mold form a space of the shape that it is desired that the outer surface of the safe shall have. 50 Thus the interior of the box may be provided with fillets 30 around the corners so that the complete safe will have rounded corners as indicated in Figs. 1, 2 and 3. This mold or box 29 is made of such depth 55 that when the factory-made inner safe struc-

ture is placed therein, with its rear parts the required distance from the bottom of the box or mold, the outer surfaces of the outer door 10 and front plate 11 will lie flush with the upper edges or rim of the box or mold as seen in Fig. 5. For the inner structure to rest upon and be supported the proper distance from the bottom of the mold, suitable blocks or spacing pieces 31 are placed on the bottom of the mold at 60 suitable intervals. With the inner structure thus supported and properly adjusted and leveled inside the mold 30, the cement 32 is poured in through the open space around the inner structure at the top of the mold, completely filling the mold all around the inner structure and among the strands of the binding webs of said structure. Any fire-proof material of suitable insulating and heat resisting properties may be used 65 and may be applied to the outer surface of the structure in any suitable manner. It is essential that such outer structure be not only insulating and heat-resisting, but that it have great resistance against disruption 70 from the force of a blow, as by falling or any other tendency or ordinary attempt to disrupt the safe. The binder, made up as described, or in any other manner, will greatly add to these resistive properties of 75 the outer structure, whatever the material may be. However, I prefer to use a good hydraulic cement of a highly fluid consistency, so that it may readily be poured into a mold and made to permeate every inter- 80 stice of the outside of the inner structure. 85

The spacing pieces 22 and 23 and 26 and 27, where they are employed are made of the fire-proof material, and formed so that they have very slight regions of contact 90 with the plates and with the webs between which they are supported. They are made long enough only to properly space the webs, dependent upon the tension throughout most of the extent of the webs. In fact, such 95 previously hardened spacing pieces are made as light and of as open construction as possible so that the fire-proof body consist of the largest possible proportion of homogeneous material. The blocks or spacers 31 are made 100 in a similar manner, and with very slight portions of their bottoms in contact with the bottom of the mold, so that the completed safe will not expose these previously hardened pieces appreciably on the surface of 105 the back thereof. Such spacing pieces cannot be pulled out from the fire-proof body to afford a means of insertion of an instrument or explosive by a burglar. 110

The flanges and the attached rear and 115 front plates project from the main part of the shell about half the depth of the fire-proof material around the sides. These flanges with the material hardened around them securely anchor the inner structure in 120 130

the material and afford a thoroughly secure support and reinforcement of the webs or other binders provided for the material. When the material has hardened the mold or 5 box 29 is torn away, leaving the safe in completed condition, except that, if desired, the outer surface may be painted or finished in any other desired manner to improve the appearance of the safe.

10 When cement is used, due to its being directly exposed to the atmosphere and not inclosed by any outer plate or other structure, it will become thoroughly dry, eliminating the trouble caused by dampness in 15 safes where the cement is inclosed by an outside structure. Good cement will, under these conditions, become so hard that it will resist burglary as well as safes with the ordinary iron or steel outer structure and 20 the insulating properties are superior to those of the safe with the metal outer structure. The metal plates become intensely heated on the outside of a safe in a severe fire, and are often the cause of the destruction 25 of the contents despite the insulating properties of the inclosed cement or other material. These plates become weakened and warped under the heat, and do not afford any marked degree of protection to the 30 inclosed fire-proof material. By inclosing the binding structure in the fire-proof wall, the binding structure is not only protected from the heat and will retain its full supporting strength, but it is enabled to hold 35 the fire-proof material much more securely than a mere covering of outer plates can.

The cost of storage, drayage and transportation of safes is largely eliminated, because the metal inner structure is the lesser 40 part of the weight of a completed safe. Thus, the user of the safe may have the comparatively light inner structure shipped from a great distance, and may procure the 45 heavy cement or other fire-proof material in the immediate vicinity. Also the molding of this fire-proof material around the inner structure calls for no great degree of skill, and may be often accomplished at less expense than it could in the factory, affording 50 another saving to the user of the safe.

While I have shown and described a certain construction specifically, I do not wish to be understood as being limited to such disclosure, but

55 What I claim as new and desire to secure by Letters Patent is:

1. In a safe, a shell, strands, forming a binder, spacing pieces, said strands being secured over said spacing pieces and thus 60 spaced from the shell, and an outer mass of protective material around said shell with said strands and spacing pieces embedded in it, said spacing pieces being of material congruent with the material of said outer mass.

2. In a safe, a shell, a reticulated web around the shell, spacing pieces bearing on the shell and supporting the web away from the shell, and an outer mass of protective material around said shell with said web 70 and spacing pieces embedded in it, said spacing pieces being of material congruent with the material of said outer mass.

3. In a safe, a shell, superposed reticulated webs surrounding the shell, spacing 75 pieces bearing on the shell and supporting said web away from the shell, spacing pieces between adjacent ones of said webs, holding them apart, and an outer mass of protective material around said shell with said webs 80 and spacing pieces embedded in it, said spacing pieces being of material congruent with the material of said outer mass.

4. In a safe, a shell, outwardly extending flanges thereon, strands, forming a binder, 85 secured around the shell and reinforced by said flanges, spacing pieces, said strands being secured over said spacing pieces and thus spaced away from the shell, and an outer mass of protective material around 90 said shell with said flanges and the strands and spacing pieces embedded in it, said spacing pieces being of material congruent with the material of said outer mass.

5. In a safe, a shell formed of a single 95 oblong plate bent around with its end portions secured together, parts of said shell being bent outward at an angle from the plates and forming the rear and front flanges thereon, strands forming a binder 100 secured around said shell between said flanges, and an outer mass of protective material around said shell with said flanges and the strands embedded in it.

6. In a safe, a shell formed of a single 105 oblong plate bent around with its end portions secured together, parts of said shell being bent outward at an angle from the plates and forming the rear and front flanges thereon, strands forming a binder secured 110 around said shell between said flanges, spacing pieces, said strands being secured over said spacing pieces and thus spaced from the shell, and an outer mass of protective material around said shell with said flanges and the strands and spacing pieces embedded in it, said spacing pieces being of a material congruent with the material of said outer mass.

7. In a safe, an inner structure comprising 120 a shell formed of a single oblong plate bent around with its end portions secured together, parts of said shell bent outward at an angle from the plate and forming rear and front flanges thereon, a plate secured 125 to the rear flanges and closing the rear of the shell, a striking plate secured to the front flanges and having an opening to the interior of the shell, a front plate secured in front of the striking plate and having an 130

opening of greater dimension than the opening in the striking plate, and a closure mounted on said front plate, entering the opening in the front plate and engaging with said striking plate.

8. In a safe, an inner structure comprising a shell formed of a single oblong plate bent around with its end portions secured together, parts of said shell being bent outward at an angle from the plate and forming rear and front flanges thereon, a plate secured to the rear flanges and closing the rear of the shell, a plate secured to the front flanges and having the opening to the interior of the shell, a closure for said opening mounted on said front plate, a striking or stop bar secured to the inside of the shell and an inner closure mounted inside said shell to close against said bar.

9. In a safe, an inner structure comprising a shell formed of a single oblong plate bent

around with its end portions secured together, parts of said shell being bent outward at an angle from the plate and forming rear and front flanges thereon, a plate secured to the rear flanges and closing the rear of the shell, a striking plate secured to the front flanges and having an opening to the interior of the shell, a front plate secured in front of the striking plate and having an opening of greater dimension than the opening in the striking plate, a closure mounted on said front plate, entering the opening in the front plate and engaging with said striking plate, a striking or stop bar secured to the inside of the shell and an inner closure mounted inside said shell to close against said bar.
